[57] CLAIM

The ornamental design for an electrical connector, as shown and described.

DESCRIPTION

FIG. 1 is a top plan view of an electrical connector showing my new design;

FIG. 2 is a bottom plan view thereof;

FIG. 3 is a front elevational view thereof;

FIG. 4 is a rear elevational view thereof;

FIG. 5 is a right side elevational view thereof, the left side elevational view being a mirror image;

FIG. 6 is a cross-sectional view thereof taken on line 6—6 of FIG. 3;

FIG. 7 is a cross-sectional view thereof as taken along line 7—7 of FIG. 3;

FIG. 8 is a top plan view thereof of an electrical connector showing my new design in the open position;

FIG. 9 is a front elevational view thereof; and

FIG. 10 is a right side elevational view thereof, the left side elevational view being a mirror image.
